UNITED STATES PATENT OFFICE.

WILLIAM A. FAIRBURN, OF SHORT HILLS, NEW JERSEY, ASSIGNOR TO THE DIAMOND MATCH COMPANY, OF CHICAGO, ILLINOIS, A CORPORATION OF ILLINOIS.

APPARATUS FOR DEHYDRATING AIR.

1,127,420.

Specification of Letters Patent.

Patented Feb. 9, 1915.

Application filed November 13, 1913. Serial No. 800,727.

To all whom it may concern:

Be it known that I, WILLIAM A. FAIRBURN, a citizen of the United States, and resident of Short Hills, in the county of 5 Essex and State of New Jersey, have invented certain new and useful Improvements in Apparatus for Dehydrating Air, of which the following is a specification.

This invention relates to an apparatus 10 for dehydrating air to adapt it for use as an efficient drying medium, and for other purposes.

The invention is particularly though not exclusively designed for use in the art of 15 manufacturing matches, in which relation it more especially concerns the treatment of primary air preparatory to its introduction to the heating and drying chamber through which wet impregnated splints are conveyed 20 preparatory to the succeeding operations of paraffining the splints and heading them with ignition composition.

The object of the present invention is to provide an apparatus of simple and efficient 25 construction and operation whereby the primary air is brought into close intimate relation with a dehydrating agent, such, for example, as calcium chlorid, and the percentage of humidity in the air thereby 30 eliminated or materially reduced; and to this end, the invention comprises various novel features of construction and arrangements of parts which will be hereinafter described and claimed.

35 In the drawings Figure 1 is a longitudinal vertical section of a dehydrating structure embodying the preferred form of my invention. Fig. 2 is a plan, on a larger scale, with the top or cover plate removed, 40 the tops of the receptacle being partly shown in section to indicate more clearly the sinuous air passages. Fig. 3 is a transverse vertical section, as on the line 3—3 of Fig. 1.

4 designates an elongated casing, one end 45 of which opens to the atmosphere or other source of primary air supply, and the other end communicates with a conduit 5 which leads to a chamber or compartment containing the match splints or other material to 50 be treated with dehydrated air. This conduit is equipped with a suitable fan or blower 6 whereby the primary air may be drawn into and through the casing and thence discharged. Supported within the 55 casing 4 to extend longitudinally thereof, in

spaced relation to each other, are basket-like receptacles containing a dehydrating agent, such as calcium chlorid. Each of these receptacles in its preferred form comprises a perforated bottom 7, sides 8 of wire 63 or other reticulated material, and V-shaped air deflecting ends 9, the whole being appropriately shaped to provide a sinuous or zig-zag receptacle of substantial length. The sinuous sides of each basket are connected at intervals by stay or cross-bars 10, and certain bars are extended laterally of the sides and provided with rollers 11 which are adapted to bear upon parallel rails 12 depending from and longitudinally of the 70 top of the casing. These rails provide trackways which constitute, in effect, a continuation of similar trackways 13 supported exteriorly of the casing, whereby the receptacles, or any of them, may be readily 75 withdrawn from or run into the casing, as need may require. The sides of the casing are provided with sinuous air deflecting plates 14 approximating in form that of the reticulated sides of the adjacent receptacles, 80 and the bottom of the casing is suitably inclined toward a median longitudinal channel or gutter 15 leading to a drain pipe 16.

By the construction just described it will be seen that atmospheric air is drawn into 85 the interior of the casing and therein subjected to the prolonged action of the dehydrating material; that is to say, the air travels in divided currents through the zig-zag longitudinal passages between and laterally of the adjacent receptacles and is progressively deflected into intimate contact with and through the opposing walls of dehydrating material as and for the purpose hereinbefore specified. It will also be seen 90 that the dehydrating material is rapidly as it is dissolved by the influence of the humidity of the air drips into the gutter 15 and flows thence to the drain pipe. Further that the receptacles, or any of them, 100 may be readily removed from the open end of the casing, re-charged with dehydrating material, and returned to the casing.

It is to be understood that my invention is not limited to the exact details of construction shown and described, as the apparatus may be greatly modified without departing from the spirit of the invention.

I claim—

1. In an apparatus of the character de- 110

- scribed, a casing, a sinuous receptacle having sides of reticulated material arranged within said casing to provide longitudinally extending air passages, and means for establishing a flow of air through said passages.
2. In an apparatus of the character described, a casing, a series of sinuous receptacles arranged therein in spaced relation to each other to provide a series of sinuous longitudinally extending air passages, said receptacles having sides of reticulated material, and means for establishing a flow of air through said passages.
- 10 3. In an apparatus of the character described, a casing, an open basket-like receptacle therein having V-shaped ends, and means for establishing a current of air through said casing.
- 15 4. In an apparatus of the character described, a casing, a sinuous receptacle having sides of reticulated material, means for removably supporting said receptacle within and longitudinally of the casing, and means for establishing a flow of air through 25 said casing.
5. In an apparatus of the character described, a casing, a trackway therein, a sinuous receptacle having sides of reticulated material, rollers on said receptacle 30 adapted to the trackway, and means for establishing a flow of air through said casing.

Signed at New York, in the State of New York this 11th day of November A. D. 1913.

WILLIAM A. FAIRBURN.
